UNITED STATES PATENT OFFICE.

JOSEPH TAGGART, OF KANSAS CITY, KANSAS.

SHIELD FOR BATTLESHIPS.

Specification of Letters Patent.

Patented May 30, 1916.

1,185,145.

Application filed October 20, 1915. Serial No. 56,962.

To all whom it may concern:

Be it known that I, JOSEPH TAGGART, a citizen of the United States, residing at Kansas City, in the county of Wyandotte, and State of Kansas, have invented certain new and useful Improvements in Shields for Battleships; and I do hereby declare the following to be a full, clear, and exact description of the invention, such as will enable others skilled in the art to which it appertains to make and use the same.

The invention relates to improvements in shields for battle ships.

The object of the present invention is to improve the construction of shields for battleships and to provide a submerged shield adapted to intercept and explode torpedoes of submarines and other vessels beyond the hull of the protected ship to prevent rupture of the same.

A further object of the invention is to provide a submerged shield of this character adapted to confine a wall of water between it and the hull of a ship so as to form a shock absorber and effectually protect ships from the effect of torpedoes exploded against the same.

Another object of the invention is to provide a shield of this character adapted to be carried by a battle ship in a folded or out of the way position when the ship is beyond the danger zone and capable of ready operation from the bridge or other point for extending the shield into a protecting position in spaced relation with the hull of the vessel.

With these and other objects in view, the invention consists in such novel features of construction, combination and arrangement of parts hereinafter fully described, illustrated in the accompanying drawing, and pointed out in claims hereto appended, it being understood that various changes in the form, proportion and minor details of construction may be resorted to without departing from the spirit or sacrificing any of the advantages of the invention.

In the drawing: Figure 1 is a vertical section view of a portion of a ship provided with a shield constructed in accordance with this invention and shown in a protecting position, Fig. 2 is a perspective view of a portion of the same. Fig. 3 is a detail view, illustrating the arrangement of the lower stay chains, Fig. 4 is a detail view of a modification of the invention,

showing a portion of a shield constructed of lattice-work, Fig. 5 is a plan view showing the shields and the separate front and rear sections in their extended position. Fig. 6 is a similar view, the shields and the sections being folded.

Like numerals of reference designate corresponding parts in the several figures of the drawing.

In the accompanying drawing in which is illustrated the preferred embodiment of the invention, 1 designates a shield, constructed of heavy sheet steel or other suitable material and conforming to the configuration of the hull 2 of a vessel and supported in spaced relation with the same by horizontal arms 3 designed to be arranged at intervals and to extend through loops 4 projecting from the upper edges of the shield and either formed integral therewith or constructed separate therefrom and suitably secured thereto. The arms 3 are pivoted at their inner ends to fixed projecting supports 5 by pivots 6 and provided with upwardly projecting heels or trip projections 7 adapted to be engaged by the loops for automatically folding the arms 3 upwardly against the sides of the ship when the shield is drawn inwardly by the fluid pressure mechanism hereinafter described. The projecting supports 5 which may be of any desired construction are provided with openings or recesses 8 adapted to receive the trip projections or heels 7 to permit the latter to lie in substantially flush relation with the upper faces or edges of the said projections when the pivoted arms are folded against the ship. The arms 3 are supported in projecting position by heavy stay chains 9 secured to the sides of the ship and to the outer ends of the arms beyond the loops 4 and the shield is also supported or braced at its lower portion by angularly related stay chains 10, which are arranged in a taut condition when the shield is in its protecting position. A stay chain may be arranged at the lower edge and at various other points on the shield as required.

When the shield 1 is in a protecting position it confines a wall of water around the hull of the ship and in practice the space is designed to be about three feet or less, so that when a torpedo is intercepted by the shield and exploded thereat the explosion will occur a sufficient distance from the hull

- of the vessel to prevent it from injuring the vessel. The shield and the wall of water form a shock absorber and the wall of water when struck with a sudden force is practically rigid and will constitute an efficient bulwark for the ship. Instead of employing a solid shell to form a shield a lattice-work shield 11 may be provided, as illustrated in Fig. 4 of the drawing. The lattice-work shield may be made lighter in structure than the solid shell 1 and it may be handled more cheaply in moving it inwardly and outwardly to its projecting position.
- 15 The fluid pressure mechanism for moving the shield inwardly and outwardly from the side of the vessel to the projecting supporting position and vice versa comprises in its construction pistons arranged at suitable intervals and consisting of a piston rod 12 connected at its outer end to the shield and extending through a stuffing box or boxing 13 of the hull and provided at its inner end with a piston head 14 operating 20 in a horizontal cylinder 15. The cylinder is provided at its ends with ports 16 and 17 connected by pipes 18 and 19 connected with suitable controlling mechanism (not shown) designed to be located at the bridge or other 25 point on a ship for enabling the shield to be instantly moved inwardly or outwardly, as may be necessary. The piston pierces the shield and is provided at its outer end with a nut 20, a tapered washer 21 being interposed between the nut and the shield. The 30 piston rod is designed to be provided with a shoulder 22 between which and the nut the shield is clamped, but any other suitable means may, of course, be provided for 35 mounting the shields on the ends of the piston rods. When the shield is moved inwardly the supporting arms are folded automatically against the hull and the shield is carried onto the fixed projecting 40 supports and is adapted to lie close to the hull of the vessel so as not to interfere with the speed of the same. The shield by being located below the surface of the water will be practically protected from injury by gun 45 fire. In practice the shield will extend from the horizontal plane of the keel or from a point below the same to within a short distance of the surface of the water so that it will be impossible for a torpedo projected 50 against the ship to strike the hull thereof, but will be intercepted by the shield and exploded at a distance from the hull which may be varied as desired.
- Separate sections 23 of the shield can be 55 adjusted on hinges 24 at the bow of the ship and connected with the remainder of the shield so as to make a continuous surface and admitting of a gradually diminishing wall of water between the shield and the ship at the bow, and separate sections 25 of
- the shield can be adjusted at the stern. The stay chains are to be adjusted at the extreme lower edge of the shield so as not to come between the shield and the skin of the ship when the shield is drawn against the side of the ship, and all attachments are to be so placed as to cause the minimum friction when the shield is folded.
- What I claim is:
1. The combination with a hull, of relatively short fixed supporting means projecting from the hull spaced supports carried by the fixed supporting means and movable to and from a projecting position, a shield slideable inwardly and outwardly on the said supports to and from the said fixed supporting means, and means for moving the shield inwardly and outwardly.
  2. The combination with a hull, of arms projecting from the hull at intervals, said arms being movably mounted, means for actuating the arms for carrying the same to and from a projecting position, a shield slidably connected with and supported by the said arms, and fixed supporting means projecting from the hull and arranged to receive the said shield when the latter is at the limit of its inward movement to relieve the arms of strain.
  3. The combination with a hull, of supports arranged at intervals and projecting from the hull, a shield slideable inwardly and outwardly on the supports and adapted to be arranged close to the hull and in spaced relation with the same, and a separate front shield section located in advance of the said shield and hinged at their front edges to the bow of the boat and movable inwardly and outwardly and adapted to form a gradually diminishing wall of water between it and the hull.
  4. The combination with a hull having fixed projecting supports, of arms pivoted to the supports and having trip projections or heels at their inner ends, a shield slidably connected with the said arms and having means for engaging the trip projections for folding the arms automatically, and means for moving the shield inwardly and outwardly.
  5. The combination with a hull, of a shield arranged exteriorly of the hull, relatively short rigid projections fixed to and extending outwardly from the hull, arms pivotally connected to the projections and slidably receiving the shield and adapted to fold against the hull, and means for moving the shield inwardly and outwardly, said shield being arranged upon and supported by the fixed projections when it is at the limit of its inward movement.
  6. The combination with a hull, of a shield arranged exteriorly of the hull and provided at its upper edge with loops, fixed projecting means carried by the hull, piv-
